SHEET EDGING APPARATUS

John L. Drake, Toledo, Ohio, assignor to Libbey-Owens-Ford Glass Company, Toledo, Ohio, a corporation of Ohio

Application June 23, 1938, Serial No. 215,331

11 Claims. (Cl. 51—96)

The present invention relates to grinding machines in general and more particularly to improved apparatus for surfacing the edges of sheets or plates of glass and the like.

5 An important object of this invention resides in the provision of grinding apparatus of relatively simplified and inexpensive construction particularly adapted for use in grinding the curved or rounded edges or corners of sheets or 10 plates of glass which are to be employed as door and window lights in automotive vehicles, although it is of course in no way restricted to such use.

Another object of the invention is the provision of grinding apparatus of the above character which will round and/or finish the curved edges or corners of the glass sheets or plates rapidly, accurately, and economically with a minimum amount of handling and also with a minimum amount of effort and attention on the part 20 of the operator, whereby uniformly rounded edges with well finished surfaces may be secured.

A further object of the invention is the provision of grinding apparatus of the above character which may be used by itself as an individual machine or in conjunction with an edging machine of the Weber type employed for grinding straight edges, to the end that both the straight and curved edges or corners of the sheets 30 may be ground in a substantially continuous manner.

Other objects and advantages of the invention will become more apparent during the course of the following description when taken in connection with the accompanying drawings.

In the drawings wherein like numerals are employed to designate like parts throughout the same:

Fig. 1 is a side elevation of an edge grinding machine constructed in accordance with the present invention;

Fig. 2 is an enlarged side view, partially broken away, of the improved corner rounding apparatus;

Fig. 3 is a vertical section taken substantially on line 3—3 of Fig. 1;

Fig. 4 is a detail section of the sheet clamping means taken substantially on line 4—4 of Fig. 2;

Fig. 5 is a detail view showing the means for securing the clamping means in inoperative position; and

Fig. 6 is a wiring diagram of the operation of the corner rounding apparatus.

Referring now to the drawings and particularly to Fig. 1, there is illustrated, by way of ex-

ample, one type of factory installation embodying two grinding units A and B constructed in accordance with the present invention for rounding opposite corners of the glass sheets or plates and between which is mounted any conventional or preferred grinding unit C which is adapted for the grinding of straight edges. There may also be provided in advance of grinding unit A and following grinding unit B the additional units D and E respectively, similar to the intermediate unit C and adapted to take care of other of the straight edges of the sheets or plates.

The glass sheets 10 to be ground are adapted to be supported on edge in a vertical position and passed successively through the several grinding units in a manner to be more clearly hereinafter described whereby to effect the grinding not only of the rounded corners but also the grinding of the straight edges. It will of course be understood that any desired number of grinding units 20 A, B, C, etc., can be arranged end to end, dependent upon the number of grinding and/or polishing elements the work requires as well as the number of straight edges and rounded corners of the sheets that are to be ground.

The intermediate grinding unit C comprises a supporting framework 11 upon which is rotatably mounted a vertical grinding wheel 12 driven in any desired manner about a horizontal axis. The grinding wheel is preferably provided with a plurality of grooves in its periphery, as well known in the art, for receiving the sheet edges to be ground. The lower portion of the grinding wheel operates within a receptacle 13 containing a suitable abrasive material, while the upper portion of said wheel projects upwardly through a slot in the bottom of a horizontal channel member 14 carried by the supporting framework 11.

Arranged within the channel member 14 at one side of the grinding wheel is a plurality of horizontally aligned conveyor rollers 15, while a plurality of similar horizontally aligned conveyor rollers 16 are arranged at the opposite side of said wheel. The rollers 15 and 16 constitute a horizontal runway leading to and from the grinding wheel and are also preferably provided with a plurality of grooves aligning with the grooves in the grinding wheel. The conveyor rollers cooperate with the grinding wheel to support the glass sheets 10 during the grinding of the straight bottom edges a thereof, as shown in Fig. 1, as the glass sheets move forwardly over and in engagement with the grinding wheel 12. The glass sheets are adapted to be moved forwardly over the grinding wheel by means of a pusher block 17.

engaging the rear edges of the glass sheets and slidably supported upon the channel member 14. The pusher block 17 can be detachably associated with a traveling sprocket chain 18 trained about sprockets 19 and 20, one of which may be suitably driven.

In order to maintain the glass sheets 10 in a vertical position and also for holding the bottom edges *a* of said sheets in proper engagement with the grinding wheel 12, there may be provided a pressure roll 21 adapted to engage and bear upon the upper edges of the glass sheets 10 as they are moved therebeneath. The pressure roll 21 may be of any conventional or preferred construction but as shown is carried by a pin 22 at the outer end of an arm 23 which is pivoted at its inner end as at 24 to a block 25. The block 25 is slidably mounted in vertical slot 26 formed in a standard 27. The block 25 is carried at one end of a cable 28 which passes upwardly over a pulley 29 and has fastened to its opposite end a counterweight 30. Formed integral with the arm 23 is an arm 31 which cooperates with said arm 23 to form a bell-crank lever. Carried by the arm 31 is a weight 32 which urges the bell-crank lever in a counter-clockwise direction to hold the pressure roll 21 downwardly in engagement with the upper edges of the glass sheets. It will be appreciated that while the intermediate grinding unit C is shown as including but a single grinding wheel 12, any desired number of wheels may be employed and these wheels may be either grinding or polishing wheels or some grinding wheels and some polishing wheels. The grinding units D and E may, if desired, be of substantially the same construction as grinding unit C.

As pointed out above, the glass sheets 10 in passing over the grinding wheel 12 of unit C are adapted to have the bottom straight edges *a* thereof ground, and with the installation disclosed, the rounded corners *b* of the sheets are adapted to be ground on unit A while the rounded corners *c* are ground on unit B. Since the units A and B are of substantially the same construction, a detailed description of only one will be given. Each unit A and B comprises a supporting framework 33 carrying at its upper end a horizontal channel member 34 comprising a bottom 35 and vertical side walls 36 and 37. Also carried by the supporting framework 33 is the grinding wheel 38 similar to grinding wheel 12 and driven in any preferred manner. The lower portion of the grinding wheel operates within a receptacle 39 containing a suitable abrasive medium, while the upper portion of said wheel projects upwardly through a slot 40 in the bottom 35 of channel member 34 as shown in Fig. 2. Supported within the channel member, adjacent one end thereof, is a channel iron 41 carrying a plurality of freely rotatable rollers 42, while supported at the opposite end of said channel member is a similar channel iron 43 carrying a series of horizontally aligned rollers 44 which are in horizontal alignment with rollers 42.

Arranged between the rollers 42 and 44 and mounted above the grinding wheel 38 is the means for supporting the glass sheets 10, said means being designated in its entirety by the numeral 45 and comprising a rockably mounted carrier or holder substantially L-shaped in side elevation. The holder 45 comprises a pair of spaced, parallel, substantially triangular corner plates 46 and 47. Secured to one end of said corner plates 46 and 47 are the substantially vertical strips 48 and 49 respectively, while a pair of

spaced horizontal strips 50 is secured to the opposite ends of said corner plates. The strips 48 and 49 are disposed at substantially right angles to strips 50. Mounted between the strips 48 and 49 upon pins 52 are a series of grooved rollers 51 which engage the inner adjacent edges of the glass sheets 10, while the bottom edges *a* thereof are supported upon a plurality of similar rollers 53 mounted upon pins 54 carried by the strips 50.

The work holder 45 is pivotally mounted upon trunnions 55 and 56 carried by the corner plates 46 and 47 respectively and provided with circular bearing members 57 and 58 which are supported within vertical slots 59 and 60 formed in supporting plates 61 and 62. The supporting plates 61 and 62 are arranged inwardly of and secured to the side walls 36 and 37 of the channel member 34, said side walls being also provided with vertical slots 63 and 64 registering with the slots 59 and 60 in plates 61 and 62. The bearing members 57 and 58 are received snugly within the slots 59 and 60 but are sufficiently free to turn therein. The bearing member 58 is adapted to be rotated to effect the desired rocking movement of the work holder, and to this end there is provided a reversible motor 65. The shaft 66 of said motor is provided with a worm 67 meshing with a worm gear 68 keyed to a shaft 69 journaled in spaced bearings 70 and 71 mounted upon a fixed support 72. The shaft 69 is connected to and drives a shaft 73 attached to bearing member 58 through an intermediate shaft 74 and universal couplings 75 and 76. Upon operation of the motor 65 in one direction, the work holder 45 will be rocked in a counter-clockwise direction and upon its operation in the opposite direction, said work holder will be rocked in a clockwise direction, with the bearing members 57 and 58 rotating in the slots 59 and 60. When the work holder is in the position illustrated in full lines in Fig. 2, the rollers 53 are in horizontal alignment with rollers 42 and are adapted to receive the glass sheets therefrom. The positioning of the glass sheets within the work holder can be effected by shoving them over the rollers 42 onto the rollers 53 and into the holder until the forward vertical edges of the sheets engage rollers 51.

When thus positioned, the sheets are adapted to be clamped in place and for this purpose there is provided the clamping means best illustrated in Figs. 2 and 4. As shown, the clamping means embodies a pair of rods 77 and 78, each being threaded at its inner end within the outer end of a connecting member 79 pivoted to the respective corner plate 46 and 47 as at 80. The rods 77 and 78 project at their outer ends through a transverse strap 81 and have threaded thereupon nuts 82 to hold the strap in fixed relation with respect to said rods. Extending between the rods 77 and 78 is a plate 83 notched at its opposite ends as at 84 to receive the rods and carrying upon its inner face a pad 85 of rubber, rubber composition, or the like, which engages the upper outer corners *d* of the glass sheets as shown in Fig. 2. Adjustment of the clamping plate 83 is effected by a bolt 86 threaded through the strap 81 and having a universal connection with clamping plate 85 as at 87. The outer end of the bolt 86 is provided with a transverse pin 88 to facilitate the turning thereof. After the glass sheets have been properly positioned in the work holder, the clamping means is moved so that the clamping plate 85 engages the upper outer corners *d* of the glass sheets and while held in this position the bolt 86 is tightened down to urge

the pad 85 into firm clamping engagement with the sheets so that the sheets will be firmly held in place during the grinding operation. During the positioning of the sheets within the work holder 45, the clamping means can be swung upwardly to engage the spring clip 89 carried by the work holder. The spring clip, as best shown in Fig. 5, is adapted to snap over the rod 77 of the clamping means. A similar spring clip 90 can be carried at the outer end of the strips 50.

After the glass sheets 10 have been properly positioned in the work holder 45, as shown in Fig. 2, the motor 65 is placed in operation to turn the holder slowly in a counter-clockwise direction, and during this rocking movement of the work holder, the corners c of the glass sheets will be moved over and in engagement with the grinding wheel 38 to effect the grinding thereof. The work holder is rotated ninety degrees so that the strips 48 and 49 will assume a horizontal position, as indicated by the broken lines in Fig. 2, and the strips 50 a vertical position, at which time the rollers 51 will be in horizontal alignment with the conveyor rollers 44. During this rocking movement of the work holder, the said holder will be permitted to move freely vertically due to the provision of the slots 59 and 60 in plates 61 and 62. When brought to this position, the operation of the motor is adapted to be automatically stopped until the sheets have been removed from the work holder whereupon the motor is again placed in operation but in a reverse direction to return the holder to its full line or starting position shown in full lines in Fig. 2.

It is believed that the operation of the apparatus will be more clearly apparent upon reference to the wiring diagram in Fig. 6. The numerals 91 and 92 designate two limit switches which are adapted to be automatically actuated by the work holder upon rocking movement thereof and these switches are connected in series with the motor 65 by wires 93 and 94 respectively. The switches 91 and 92 are also connected by wires 95 and 96 to the negative main line 97. Electric current is fed to the motor 65 from the positive main line 98 through a wire 99, snap switch 100 having contacts 101 and 102, and wires 103 and 104. In starting the rocking movement of the work holder, the operator first manually closes switch 100 by moving it into engagement with contact 101 and when this is done the current will enter the motor 65 from the positive main line 98 through wire 103 and passes therefrom through switch 91 to the negative main line 97. When the work holder reaches the end of its rocking movement in a counter-clockwise direction, the said holder will automatically open switch 91 to break the circuit through the motor 65 and bring the same to a stop. The work holder remains in this position until the operator again manually closes switch 100 by moving it to engage contact 102, at which time the current entering the motor 65 through wire 104 will pass therefrom through switch 92 to the negative main line 97. When the motor is thus placed in operation, the work holder will be rocked in a clockwise direction to return it to starting position and when it reaches such position, it will 70 act to automatically open switch 92, thereby again breaking the circuit through the motor to bring it to a stop. The switches 91 and 92 are preferably of the type which will be maintained in open position only during the time the work holder is in engagement therewith, and just as

soon as the work holder moves out of engagement with the switches, they will automatically close. The working movement of the work holder 45 will be limited in either direction by a set screw 105 engaging an angle iron 106 carried by 5 said work holder.

It is to be understood that the form of the invention herewith shown and described is to be taken as the preferred embodiment of the same, and that various changes in the shape, size and arrangement of parts may be resorted to without departing from the spirit of the invention or the scope of the subjoined claims.

I claim:

1. In apparatus for grinding the curved edge 15 of a sheet or plate of glass or the like, a rotary grinding wheel positioned to rotate about a substantially horizontal axis, a horizontal runway leading to and from said grinding wheel including a plurality of horizontally aligned conveyor 20 rollers arranged at each side of the wheel, a work holder mounted above the grinding wheel for supporting the sheet to be ground on edge in a substantially vertical position including two series of rollers arranged at substantially right 25 angles relative to one another and engageable by the adjacent edges of said sheet, and means for rocking said work holder first in one direction to move the curved edge of the sheet to be ground over and in engagement with the grinding wheel and then in the opposite direction to return it to starting position, one of said series of rollers being disposed in substantially horizontal alignment with said conveyor rollers at the completion of the rocking movement of said 30 work holder in either direction.

2. In apparatus for grinding the curved edge of a sheet or plate of glass or the like, a rotary grinding wheel positioned to rotate about a substantially horizontal axis, a horizontal runway 40 leading to and from said grinding wheel including a plurality of horizontally aligned conveyor rollers arranged at each side of the wheel, a work holder mounted above the grinding wheel for supporting the sheet to be ground on edge in a substantially vertical position including two series of rollers arranged at substantially right angles relative to one another and engageable by the adjacent edges of said sheet, means for rocking said work holder first in one direction to 45 move the curved edge of the sheet to be ground over and in engagement with the grinding wheel and then in the opposite direction to return it to starting position, one of said series of rollers being disposed in substantially horizontal alignment with said conveyor rollers at the completion of the rocking movement of said work holder in either direction, and means for automatically bringing the said work holder to a stop when it reaches the end of its rocking movement in either 50 direction.

3. In apparatus for grinding the curved edge of a sheet or plate of glass or the like, a rotary grinding wheel positioned to rotate about a substantially horizontal axis, a horizontal runway 65 leading to and from said grinding wheel including a plurality of horizontally aligned conveyor rollers arranged at each side of the wheel, a work holder arranged above the grinding wheel for supporting the sheet to be ground on edge 70 in a substantially vertical position including two series of rollers arranged at substantially right angles relative to one another and engageable by the adjacent edges of said sheet, means for mounting said work holder for free vertical and 75

rocking movement, and means for rocking said work holder first in one direction to move the curved edge of the sheet to be ground over and in engagement with the grinding wheel and then in the opposite direction to return it to starting position, one of said series of rollers being disposed in substantially horizontal alignment with said conveyor rollers at the completion of the rocking movement of said work holder in either direction.

4. In apparatus for grinding the curved edge of a sheet or plate of glass or the like, a rotary grinding wheel positioned to rotate about a substantially horizontal axis, a horizontal runway leading to and from said grinding wheel including a plurality of horizontally aligned conveyor rollers arranged at each side of the wheel, a work holder arranged above the grinding wheel for supporting the sheet to be ground on edge in a substantially vertical position including two series of rollers arranged at substantially right angles relative to one another and engageable by the adjacent edges of said sheet, means for mounting said work holder for free vertical and rocking movement, a reversible motor for rocking said work holder first in one direction to move the curved edge of the sheet to be ground over and in engagement with the grinding wheel and then in the opposite direction to return it to starting position, one of said series of rollers being disposed in substantially horizontal alignment with said conveyor rollers at the completion of the rocking movement of said work holder in either direction, and limit switches actuated by the said work holder when it reaches the end of its rocking movement in either direction to stop said motor.

5. In apparatus for grinding the curved edge of a sheet or plate of glass or the like, a rotary grinding wheel positioned to rotate about a substantially horizontal axis, a horizontal runway leading to and from said grinding wheel including a plurality of horizontally aligned conveyor rollers arranged at each side of the wheel, a work holder mounted above the grinding wheel for supporting the sheet to be ground on edge in a substantially vertical position including two series of rollers arranged at substantially right angles relative to one another and engageable by the adjacent edges of said sheet, means for rocking said work holder first in one direction to move the curved edge of the sheet to be ground over and in engagement with the grinding wheel and then in the opposite direction to return it to starting position, one of said series of rollers being disposed in substantially horizontal alignment with said conveyor rollers at the completion of the rocking movement of said work holder in either direction, and means carried by the said work holder and engaging the said sheet for securing it in place.

6. In apparatus for grinding the curved edge of a sheet or plate of glass or the like, a rotary grinding wheel positioned to rotate about a substantially horizontal axis, a horizontal runway leading to and from said grinding wheel including a plurality of horizontally aligned conveyor rollers arranged at each side of the wheel, a work holder arranged above the grinding wheel for supporting the sheet to be ground on edge in a substantially vertical position including two series of rollers arranged at substantially right angles relative to one another and engageable by the adjacent edges of said sheet, means for mounting said work holder for free vertical and rocking

movement, means for rocking said work holder first in one direction to move the curved edge of the sheet to be ground over and in engagement with the grinding wheel and then in the opposite direction to return it to starting position, one of said series of rollers being disposed in substantially horizontal alignment with said conveyor rollers at the completion of the rocking movement of said work holder in either direction, and clamping means pivotally carried by said work holder and engaging the outer edge of said sheet for securing it in position in said work holder.

7. In apparatus for grinding the curved edge of a sheet or plate of glass or the like, a rotary grinding wheel positioned to rotate about a substantially horizontal axis, a horizontal runway leading to and from said grinding wheel including a plurality of horizontally aligned conveyor rollers arranged at each side of the wheel, spaced vertical plates mounted above the grinding wheel and having vertically disposed slots therein, a work holder arranged between said plates for supporting the sheet to be ground on edge in a substantially vertical position including two series of rollers arranged at substantially right angles relative to one another and engageable by the adjacent edges of said sheet, trunnions carried at opposite sides of said work holder and having bearing members rotatably received in said slots, and means for driving one of said bearing members to rock said work holder first in one direction to move the curved edge of the sheet to be ground over and in engagement with the grinding wheel and then in the opposite direction to return it to starting position, one of said series of rollers being disposed in substantially horizontal alignment with said conveyor rollers at the completion of the rocking movement of said work holder in either direction.

8. In apparatus for grinding the curved edge of a sheet or plate of glass or the like, a rotary grinding wheel positioned to rotate about a substantially horizontal axis, a horizontal runway leading to and from said grinding wheel including a plurality of horizontally aligned conveyor rollers arranged at each side of the wheel, spaced vertical plates mounted above the grinding wheel and having vertically disposed slots therein, a work holder arranged between said plates for supporting the sheet to be ground on edge in a substantially vertical position including two series of rollers arranged at substantially right angles relative to one another and engageable by the adjacent edges of said sheet, trunnions carried at opposite sides of said work holder and having bearing members rotatably received in said slots, a reversible motor for driving one of said bearing members to rock said work holder first in one direction to move the curved edge of the sheet to be ground over and in engagement with the grinding wheel and then in the opposite direction to return it to starting position, one of said series of rollers being disposed in substantially horizontal alignment with said conveyor rollers at the completion of the rocking movement of said work holder in either direction, and limit switches actuated by the said work holder when it reaches the end of its rocking movement in either direction to stop said motor.

9. In apparatus for grinding the curved edge of a sheet or plate of glass or the like, a rotary grinding wheel positioned to rotate about a substantially horizontal axis, a horizontal runway leading to and from said grinding wheel, a work holder mounted above the grinding wheel for sup-

porting the sheet to be ground on edge in a substantially vertical position including two sheet supporting means arranged at substantially right angles relative to one another and engageable by the adjacent edges of said sheet, and means for rocking said work holder first in one direction to move the curved edge of the sheet to be ground over and in engagement with the grinding wheel and then in the opposite direction to return it to starting position, one of said sheet supporting means being disposed in substantially horizontal alignment with said runway at the completion of the rocking movement of the said work holder in either direction.

10. In apparatus for grinding the curved edge of a sheet or plate of glass or the like, a rotary grinding wheel positioned to rotate about a substantially horizontal axis, a horizontal runway leading to and from said grinding wheel, a substantially L-shaped work holder mounted above the grinding wheel comprising two portions arranged at substantially right angles relative to one another, means carried by each portion of the work holder and engageable by the adjacent edges of the sheet for supporting the sheet to be ground on edge in a substantially vertical position, and means for rocking said work holder first in one direction to move the curved edge of the sheet to be ground over and in engagement with the grinding wheel and then in the opposite di-

rection to return it to starting position, the sheet supporting means carried by one of the portions of the work holder being disposed in substantially horizontal alignment with said runway at the completion of the rocking movement of the said work holder in either direction.

11. In apparatus for grinding the curved edge of a sheet or plate of glass or the like, a rotary grinding wheel positioned to rotate about a substantially horizontal axis, a work holder mounted above said grinding wheel having means for supporting the sheet to be ground on edge in a substantially vertical position, means for rocking said work holder first in one direction to move the curved edge of the sheet to be ground over and in engagement with the grinding wheel and then in the opposite direction to return it to starting position, and clamping means for securing the sheet in position within said work holder including a pair of rods positioned at opposite sides of the said work holder and pivoted thereto at their inner ends, means for connecting said rods together at their outer ends, a clamping plate slidably received between said rods and engaging the outer edge of the sheet, and means carried by the means connecting said rods together for adjusting said plate inwardly to urge the said sheet into firm clamping engagement with the supporting means therefor.

JOHN L. DRAKE. 30
